UNITED STATES PATENT OFFICE.

CHARLES H. MATHER, OF ESSEX, CONNECTICUT, ASSIGNOR OF ONE-HALF
TO GEORGE E. KNOWLES, OF BROOKLYN, NEW YORK.

STORE-BIN.

SPECIFICATION forming part of Letters Patent No. 718,647, dated January 20, 1903.

Application filed November 10, 1902. Serial No. 130,802. (No model.)

To all whom it may concern:

Be it known that I, CHARLES H. MATHER, a citizen of the United States, residing in Essex, in the county of Middlesex and State of Connecticut, have invented a certain new and useful Improvement in Store-Bins, of which the following is a specification.

Where small hardware, provisions, and the like are weighed out and sold from bins, two principal difficulties are often met with. In taking out the quantities to be weighed there is a frequent spilling of small amounts around the bin and on the floor, which causes waste and dirt. In returning to the bin the surplus left in the scoop or other device after weighing, it frequently occurs that in haste this surplus is accidentally thrown back into the wrong bin, thus confusing sizes or qualities, or both.

It is the object of this invention to provide a cheap and simple means which shall take up a minimum of room and whereby the above-named difficulties may be obviated.

A preferred form of this invention is shown in the accompanying drawings, wherein—
Figure 1 shows in perspective a portion of a nest of bins as preferably used under a store-counter. Fig. 2 is a perspective view of a single bin made in accordance with this invention. Fig. 3 is a perspective view of the weighing-drawer shown as holding a quantity of nails. Fig. 4 is a plan view of a single bin, and Fig. 5 is a median vertical section of the same.

The main storage-box 1 of the bin may be of any preferred shape and size consistent with my general construction, but I have found the form shown a convenient one for nails and small hardware. In any case it is preferred to supply an inclined floor at the front, as shown at 2, as this facilitates scooping the material stored out of the front of the bin. The bins may be used singly or in rows within an appropriate casing 3. (See Fig. 2.) In the latter case each bin is preferably contained within a separate compartment and is provided with rollers 4 to facilitate bringing the bin forward for refilling, &c. These rollers lift the body 1 sufficiently to permit the bottom of the weighing-drawer 5 to be slipped easily under it, as shown in Fig. 5. This drawer is preferably as high as the front

of the main body 1 and is provided with a handle 6, whereby it may be pulled forward, as shown in Figs. 1, 2, and 5. The sides of this drawer embrace those of the main body 55 and slide along the same until the front of the drawer fits flat against the front of the body, as shown at 7 in Fig. 1. A handle 8 is preferably used in the front of the body 1 and should be let into the said front, so as to 60 cause no obstruction to the front of the drawer. The main body is kept centered within its compartment by cleats 9 on each side thereof, so as to insure easy slipping inward of the weighing-drawer 5. This is not essential to 65 my broad invention, and indeed it is to be understood that I am not confined in my claims to the use of a movable main body in my bin.

In using this bin the following course is 70 pursued. The drawer 5 is first pulled forward, as in Fig. 5, and approximately the amount of goods required is drawn forward out of the body 1 by the hand or otherwise. (See Fig. 5.) The drawer thus charged (see 75 Fig. 3) is carried to the scales and the desired amount is weighed out. The salesman then returns to the nest of bins with the surplus goods in the drawer and his eye is at once caught by the bare front of the body 1, as 80 shown at 10 in Fig. 1. He knows that the drawer in his hand must be fitted to that body so exposed, and therefore throws the surplus goods into that box before returning its drawer to its place. Accidental placing 85 of the surplus in the wrong box is thus avoided. It will also be seen that in first taking the goods out of the body 1 the fact that the drawer embraces the box under it and on each side prevents accidental spilling 90 of any of the goods on the floor when removing them from the main body.

What I claim is—

1. In a store-bin, a main body and a weighing-drawer fitting the front thereof and embracing said front, substantially as described. 95
2. In a store-bin, a main body and a weighing-drawer of the same height as the front of said body, said drawer fitting the front of said body and embracing the same, substantially as described. 100
3. In a store-bin, a main body having an

inclined floor in front and a weighing-drawer fitting the front thereof and embracing said front, substantially as described.

4. In a store-bin, a main body having a low front, an inclined floor leading up to the upper edge of said front, and a weighing-drawer of the same height as the front of the body, said drawer fitting the front of the body and embracing the same.
5. In a store-bin, a compartment, a main body on rollers within said compartment and a weighing-drawer fitting the front thereof and embracing said front.
6. In a store-bin, a compartment, a main

body on rollers within said compartment, ¹⁵ spacing-pieces at the sides of said main body, a weighing-drawer embracing and fitting the front of said body and handles on said body and said drawer, the body-handle being let into the front.

7. A nest of store-bins each in its own separate compartment, each bin comprising a main body and a weighing-drawer fitting and embracing the front of said body.

CHARLES H. MATHER.
